UNITED STATES PATENT OFFICE.

GEORGE W. DUNHAM, OF NEW YORK, N. Y., ASSIGNOR TO THE MILITOR CORPORATION
OF NEW YORK, N. Y., A CORPORATION OF NEW YORK.

LUBRICATING SYSTEM.

1,399,943.

Specification of Letters Patent. Patented Dec. 13, 1921.

Application filed January 8, 1919. Serial No. 270,108.

To all whom it may concern:

Be it known that I, GEORGE W. DUNHAM, a citizen of the United States, residing at New York, in the county of New York and State 5 of New York, have invented a certain new and useful Improvement in Lubricating Systems, of which the following is a full, clear, and exact description, reference being had to the accompanying drawings.

This invention relates to oil collecting, restraining, and separating means, especially suitable for use with gas engines, particularly those of motorcycles and other vehicles.

The general objects are to provide simple and reliable means for collecting the lubricating oil; and (in the present embodiment) for restraining it against flooding the crank case of the engine and leaking out as through the end crank shaft bearings when the engine is tilted, as when ascending or descending grades; and to provide means for effectually separating sediment from the oil and which means is not likely to become clogged, nor liable to get out of order; but 25 is simple, durable, positive of action, and comparatively inexpensive.

Other and more specific ends in view are the production of a strong well shaped oil pan, preferably formed of a single piece 30 of sheet metal, for application to the bottom of the engine casing; to incorporate, preferably in the casing, deflectors which extend from the ends of the crank case inward until their inner ends are separated only a comparatively short distance from each other 35 thereby to confine the oil within the oil pan when the engine is tilted endwise materially; and to provide an oil trap or separating means for incorporation in the oil circulating system and wherein a proper suction 40 is maintained at all times so long as there is an appreciable amount of oil in the system, thereby insuring satisfactory lubrication.

To these several ends my invention may be 45 defined as consisting of the combinations of elements set forth in the claims annexed hereto and illustrated in the accompanying drawings wherein Figure 1 is a central longitudinal section through the crank case of an internal combustion engine having my invention incorporated therein; and Fig. 50 2 a somewhat enlarged transverse section on the line 2-2 of Fig. 1.

The lower half of the crank case—the only portion of the engine structure which

it is necessary to show to fully illustrate my invention—is designated 1, and within the bottom thereof are situated deflectors 2 and 3, shown as formed integral with the crank 60 case, and which extend from the end walls of the case inward and slightly downward until their inner ends approach each other quite closely at about the longitudinal center of the crank case. 65

The lower end of the crank case is provided with a flat peripheral bead 5 to which is applied the horizontal flange 6 of the oil pan 7, the pan being preferably made of a single piece of sheet metal, formed to produce a shallow rectangular basin having its edge flared outwardly to produce the flange 6 and then downwardly to strengthen the flange. The flange 6 is provided with holes 70 that register with threaded apertures in the bead 5 for the reception of retaining screws 8. A gasket 10 of suitable packing material is interposed between the flange and bead.

Shown as situated near the rear end of the oil pan is an oil trap which constitutes 80 the separating means hereinbefore referred to. This trap, in its present form, consists of a cylindrical screen inclosure 12, having a flange 13 applied to its lower end by means of which it is secured to the bottom of the 85 oil pan 7. The deflector 3 has an opening 14 above and substantially concentric with the screen inclosure 12 within which is fitted an inverted sheet metal cup 15, the cylindrical wall 16 whereof descends about 90 the inclosure 12 until its lower end is spaced only a short distance above the bottom of the oil pan. Where the cylindrical wall of the cup joins the circular wall 17 thereof, it is flared outward and crimped against the 95 circular wall to produce a flange adapted to be clamped or confined between the upper surface of the deflector 3 and a ring 18 that is secured to the thickened annular portion of the deflector which surrounds the opening 14, as by rivets 20.

The circular wall 17 has a central aperture through which a tube 21 depends, the material of the wall being turned upward about the tube for attachment thereto. The 105 lower end of the tube is cut diagonally and the lowest point thereof is spaced only a short distance from the bottom of the oil pan. The tube 21 leads to an oil pump (not shown), such as are common to engines of the 110 class herein referred to, and which acts to suck the oil from within the screen inclosure

12. After the oil has been circulated through the lubricating system of the engine, it is thrown off and drains down into the crank case and is conveyed by the deflectors 2 and 3 to the oil pan 7 in which it is collected and from which it is drawn into the screen inclosure 12. When the screen is free from sediment, the oil flows inward through the lower portion thereof; 5 but as the sediment collects about the screen and clogs it from its lower end gradually upward, the oil is compelled to flow upward between the wall 16 and screen by reason of the facts that the cup 15 is air tight and the wall 16 thereof extends below the minimum oil level, so that the exposure of oil within the lower end of the cup is subjected to the suction and is drawn upward thereby until it finds access to the interior of the screen 10 either through it, or over the upper edge thereof if the screen has been allowed to become clogged throughout the entire extent of its area.

Having thus described my invention what 25 I claim is:—

1. In a separator, the combination of an inclosure 12, a suction duct 21 having its receiving end within said inclosure, and a substantially fluid tight casing 16 spaced 30 from and inclosing one end and a portion of the sides of said inclosure.
2. In a lubricating system of the character set forth, the combination of two substantially horizontal walls spaced one above the other, an inclosure supported by the lower wall, a suction duct having its receiving end disposed within said inclosure, and a casing carried by the upper wall and extending downward over the inclosure.
3. In a lubricating system of the character set forth, the combination of two substantially horizontal walls spaced one above the other, a screen inclosure supported by the lower wall, a suction duct having its receiving end disposed within the inclosure, the upper wall having an aperture above the inclosure, and an open bottom casing supported within said aperture and extending down over the inclosure.
4. In a lubricating system of the character set forth, the combination of two substantially horizontal walls spaced one above the other, of an inclosure supported by the lower wall, a suction duct having its receiving end disposed within the inclosure, the upper wall having an aperture above the inclosure, and an open bottom casing supported within said aperture and extending down over the inclosure, said casing being provided with a 45 peripheral flange resting upon the upper wall.
5. In a lubricating system of the character set forth, the combination of two substantially horizontal walls spaced one above the other, of an inclosure supported by the lower

wall, a suction duct having its receiving end disposed within the inclosure, the upper wall having an aperture above the inclosure, an open bottom casing supported within the aperture and extending down over the inclosure, the casing having a peripheral flange bearing upon the upper wall, a clamping ring surmounting said flange, and means securing the ring to said upper wall.

6. In a separator, the combination of an inclosure 12, a casing 16 spaced from and extending over the top of said inclosure and down about the inclosure into proximity to the bottom thereof, and a suction tube 21 projecting into the casing through the top wall thereof and having its receiving end disposed within the inclosure.

7. A separator comprising an open top inclosure 12, a suction duct 21 having its receiving end disposed therein, and a casing 85 extending over the top and down around the said inclosure and spaced therefrom.

8. In combination with the crank case of an engine, said crank case having a supporting element situated in the bottom thereof, 90 an oil pan for application to the bottom of the crank case, an inclosure within and carried by the oil pan, a casing member carried by the aforesaid supporting element and sustained thereby over and about the inclosure, 95 the wall of the casing being spaced from that of the inclosure, and a suction duct having its receiving end disposed within the inclosure.

9. In combination with an engine, an oil 100 pan removably attached to the bottom of the engine crank case, and a separator comprising two open ended casing elements one carried by the crank case and the other by the oil pan and which are disposed in telescopic relation to each other when the oil pan is attached to the crank case.

10. The combination with an engine, of an oil pan applied to the crank case thereof, an inclosure within and carried by the oil pan, 110 an open ended casing supported by the crank case over and about the inclosure, and a suction tube carried by the engine and extending downward through the top wall of the casing with its suction end disposed within 115 the inclosure.

11. In a separator, the combination of a casing, a vertically disposed screen within the casing, a suction duct having its receiving end disposed within the casing on one 120 side of the screen, the casing incorporating an impervious wall spaced from the opposite side of the screen, the casing defining a fluid-tight inclosure for said screen except for an interruption of the aforesaid wall below the 125 top of the screen.

In testimony whereof, I hereunto affix my signature.

GEORGE W. DUNHAM.
